CLAIM

The ornamental design for a dispenser housing, as shown.

DESCRIPTION

A portion of the disclosure of this patent document contains material to which a claim for copyright is made. The copyright owner has no objection to the facsimile reproduction by anyone of the patent document or the patent disclosure as it appears in the Patent and Trademark Office patent file or records, but reserves all other copyright rights whatsoever.

FIG. 1 is a perspective view of the dispenser housing in an open position;

FIG. 2 is a perspective view of the dispenser housing in a closed position;

FIG. 3 is a top plan view of dispenser housing of FIGS. 1 and 2;

FIG. 4 is a front view in elevation of the dispenser housing of FIGS. 1 and 2;

FIG. 5 is a right side view in elevation of the dispenser housing of FIGS. 1 and 2;

FIG. 6 is a rear view in elevation of the dispenser housing of FIGS. 1 and 2;

FIG. 7 is a left side view in elevation of the dispenser housing of FIGS. 1 and 2; and,

FIG. 8 is a bottom plan view of the dispenser housing of FIGS. 1 and 2.

The areas within dashed lines, that is, the back of the dispenser housing and the interior of the dispenser housing form no part of the claimed design.

Features shown in broken lines, that is, the hinge, dispensing aperture, auxiliary access door on the top of the dispenser and other features are shown to illustrate environment and likewise form no part of the claimed design.

The broken lines and the dashed lines form no part of the claimed design.
